UNITED STATES PATENT OFFICE.

HENRY ARTHUR THOMPSON, OF MANCHESTER, ENGLAND.

EXPEDITING AND SAFEGUARDING RAILWAY TRAFFIC.

1,185,024.

Specification of Letters Patent. Patented May 30, 1916.

Application filed January 27, 1915. Serial No. 4,654.

To all whom it may concern:

Be it known that I, HENRY ARTHUR THOMPSON, subject of the King of Great Britain and Ireland, and resident of Withington, Manchester, in the county of Lancaster, England, have invented certain new and useful Improvements for Expediting and Safeguarding Railway Traffic, of which the following is a specification.

10 My invention relates to direct or indirect control of "line" signals, or of signaling appliances by trains and to the provision of means for enabling signalmen to watch the progress of trains which are out of sight through fog or physical obstruction.

15 The object of my invention is therefore the safeguarding and expediting of railway traffic and its chief advantages are that rail bonding is practically done away with, and 20 that long lengths of track may be controlled.

A further advantage is that main line signals may be controlled from sidings, branch lines, or the like.

25 My invention is particularly adapted for use with electrical power signaling, that is to say, for the direct control of light signal levers.

30 The presence of a train in a section or controlled portion of the track is indicated in the signal box by the absence of an indicator light, while a section unoccupied is shown by the glowing of a green lamp. The progress of a train through a section is announced by the glowing of lamps of various colors.

35 It is necessary in order that the full scope of my system may be attained that the metal periphery of some of the wheels of each vehicle should be metallically connected with the relative axles. Such connection however is not essential for the control of the semaphores. I propose to describe a method whereby electro-magnetic devices may either 40 control the signal levers directly (as is possible in the electrical operation of semaphores) or may control signal levers and semaphores indirectly. The electro-magnetic devices in my invention are actuated 45 by automatically varying the resistance in a circuit in the manner hereinafter described.

50 In order that my said invention may be understood I append hereunto two sheets of drawings in which,

55 Figure 1 shows the signal box and track wiring and Fig. 2 the cut-out device, while

Fig. 3 shows the method of controlling from one line a signal relative to another line.

From one pole of a secondary battery situated in the signal box from which the controlled signal A Figs. 1 and 3 is operated an insulated conductor B¹, after being connected to certain necessary pieces of apparatus is carried to a suitable position contiguous to or in advance of said signal. The choice of such position will depend on the practicability of making a sufficient number of wheels and axles conductive of electricity. The said insulated conductor is connected to a rail length R¹ on the track, such rail length being insulated from the adjacent rail lengths and from the track; or two or more rail lengths may be bonded together if the vehicles are very long and the rail lengths short. Or again several rail lengths may be bonded together in order that a warning bell or lamp may be actuated in the signal-box for a sufficient length of time if it be impracticable to render the wheels of the coaches conductive. A "short circuit" between one rail and the opposite rail should be constantly maintained through one or more axles during the passage of the train over the insulated rail length in order that the full benefit of my invention may be obtained. The insulated rail length R¹ and the opposite rail R² are connected by a branch wire in series with a bridging coil H¹ of high resistance. (I use the term high resistance merely to distinguish from the low resistances herein referred to. As a matter of fact the "high resistance" may not exceed 100 ohms).

The uninsulated rail R² is then earthed as its resistance would vary with the weather owing to the dirty joints and at times would not conduct at all. A good "earth" is therefore essential. A return wire must be used instead of the earth where more than one length of track is controlled from the same battery, and the opposite rail must also be insulated for the same distance as its neighbor. As a general rule a return wire would be used. At the remote end of the section or controlled portion of the track a similar arrangement obtains. It is immaterial which rail is insulated provided the opposite rail is "earthed." A second insulated wire B² leading from the remote insulated length R² is carried back to the same signal box, where it is connected to the battery, and

may also enter the signal box adjacent to the remote insulated length R^2 in order that an indicator or other suitable device may be actuated therein for observation or locking purposes. In the resultant circuit, which I term the "black circuit" to facilitate description, is an electro-magnetic cut-out device Fig. 2 whose coils are of low resistance. Between such coils is a high resistance coil H^3 equal in value to the resistance of one of the bridging coils on the track. Attached to the armature I of the said device is a light rod 2 which on rising with the armature causes two springs 3 and 4 to make contact and thus to short circuit the high resistance coil H^3 . I do not restrict myself to the use of this particular kind of cut-out device. Also in the black circuit are the black coils of the two low resistances doubly wound electro-magnets S and D the functions of which are to control the signal levers either directly or indirectly as herein-before stated. In the black circuit is a low resistance timing lamp 5 or bell of low resistance whose function is to glow or ring during the passage of the train over the insulated rail R^1 and R^2 . In the same circuit is also a switch X operative by the device controlled by the electro-magnets S and D . In Fig. 1 the device in question is the signal lever itself. It is immaterial for the purpose of this invention how the necessary electrical contact is made and broken. It is obvious that this is possible in a great variety of ways. My invention simply shows how two holding magnets may be energized and deenergized for the purpose of direct or indirect signal control. In the circuit of the said switch at safety position is a red lamp 6 of low resistance. In the circuit of the switch at danger is a green lamp 7 of low resistance. In the white circuit W are the white coils of the two doubly-wound electro-magnets S and D whose function as aforesaid is to control the signal levers or semaphores. Also in the white circuit is a resistance coil 8 by means of which the strength of the current in such circuit is fixed. Also in the white circuit is an indicator lamp 9 or the like whose function is to show that the white circuit is not disconnected and that the battery is not run down. A current flows continuously through the white circuit, energizing the doubly-wound electro-magnets S and D ; the direction of the flow of such current around the cores being opposite to the direction in which the current in the black circuit flows around them. Normally a comparatively weak current flows through the black circuit there being in such circuit the three high resistances, the resistance of the line wire, the two low resistance coils of the electro-magnetic cut-out and the black coils of the other two-electro-magnets as well as the resistance

of the red or the green lamp and the resistance of the timing lamp or the bell.

My invention may best be further described by indicating its manner of working. Thus:—let the signal lever be in the forward or safety position as shown in Fig. 1. A fairly strong current flowing through the white coil of electro-magnet S , ineffectually opposed by the normal current in the black coil of the same electro-magnet, holds any suitable device to the poles of such electro-magnet, the said device in turn preventing the lever from flying back to danger. In Fig. 1 the lower end of an iron signal lever is held by a single core electro-magnet S but it is to be clearly understood that the holding electro-magnets may be of any suitable type and that they may control a shoe or any secondary mechanical or electrical device capable of effecting the necessary purpose. When the wheels of the engine reach the short insulated length of rail R^1 the bridging resistance H^1 is short-circuited, the current flowing from one rail through the axles and the wheels to the other rail. The current in the black coil of the electro-magnet S is now rendered equal in value to that in the white coil of the same electro-magnet and the red lamp 6 glows and the signal lever would be released, or would be capable of being released by the signalman, but for the fact that the electro-magnetic cut-out is actuated by the strengthened current in the black circuit. The high resistance between the two coils of the cut-out device is cut out of the black circuit and the signal lever is still held, the current in the black circuit being now stronger than that in the white circuit. Further the timing lamp 5 which until the two high resistances are simultaneously cut out glows but feebly now glows brightly and continues to do so until the whole train has cleared the insulated rail length. I assume that a sufficient number of wheels and axles are rendered conductive otherwise the semaphore would be restored as soon as the engine and tender cleared the insulated rail length. If only the wheels and axles of the engine and tender are conductive the rule forbidding the restoration of the signal until the passage of the whole train past such signal would be inoperative unless the insulated rail length occupy a position well inside the controlled portion of the line and this contingency I consider in my invention. When the last vehicle has cleared the insulated rail length the currents in the white and black coils of electro-magnet S are equalized (the high resistance H^3 in the signal box still being cut out) and the said currents opposing each other the magnetic effect is *nil*; and the signal lever flies back to danger. The black circuit is momentarily disconnected and the signal box high resistance is again brought

into the black circuit, with the result that the current in the white coil of electro-magnet D is only opposed by the weak current in the black circuit. The signal lever or controlling device is thus held at danger. The process is repeated at the remote end of the controlled portion of the track, the signal-lever controlling the restored signal at the entrance of such portion not yet however being capable of movement. The timing lamp 5 glows during the passage of the train over the second insulated rail length as also does the green lamp 7. The high resistance in the signal box being again cut out, the green lamp continues to glow when the train has completely cleared the section and the currents in the white and black coils of electro-magnet D being equal in strength and opposite in direction allow the signal lever 20 to be pulled forward when required.

Fig. 1 shows the inner segment 10 of the signal lever switch connecting two outer segments 11 and 12. In the danger position the two other outer segments 13 and 14 25 would be connected instead.

Intermediate places may be brought under observation in a similar manner to that described without interference with the signals. A suitable length of rail R^3 is 30 insulated as before. The insulated length is connected with one pole of the battery in series with say a purple lamp or a bell or both in the signal box. The opposite rail is also insulated for the same distance 35 and connected to the other pole of the battery. When a train passes over the intermediate length the high resistance H^4 between the rails is short-circuited and the lamp 15 glows or a bell rings; or both a 40 lamp and a bell are actuated. If desired two lamps may be used, one operative by the normal current and the other by the strengthened current due to the passage of the train.

45 My invention may be used for "lock and block" working or for the control of signaling appliances generally.

I may, if required, include in the black and white circuits doubly-wound electro-magnets in series with S and D to control 50 the semaphores as well as the signal levers on exactly the same principle. I may use my system to control the semaphores only, the electro-magnets S and D holding the 55 semaphores directly or relaying currents or breaking circuits in any manner whatsoever, the said electro-magnets being placed in any suitable place provided the coils are in the black and white circuits respectively. 60 The switch controlling the black circuit may be mechanically actuated by the semaphore itself.

It is evident that if the black circuit contain an additional high resistance or bridging coil and that if this resistance be cut out 65

of the said circuit an alteration in the current strength therein will be effected. I propose therefore to use a third bridging coil, to increase the voltage of the battery, and to insulate portions of each rail to effect 70 the following purpose. If a controlled section contains a siding or branch line it is obvious that a train entering such side road would fail, under the conditions hereinbefore prescribed, to actuate a second time the 75 electro-magnetic cut-out whose final function is to cause the green lamp to glow and to allow the signal-lever to be pulled to safety. But it is imperative that this result should be attained as soon as the train is 80 well inside the siding or branch road. By using a return wire and a third bridging coil it is accomplished as follows:—Fig. 3 shows in a simple manner the black circuit modified to suit the circumstances, the signal box details being omitted. A third bridging coil H^5 is placed in series with H^1 and H^2 at the entrance to the siding or branch line (or well inside especially if it be impracticable to render the wheels of the 85 coaches conductive). It is clear that the necessary alteration in the value of the current will be effected whether the train enters the siding or branch line or whether it proceeds to the end of the controlled portion of 90 the main line since the bridging coil H^5 relative to the siding and the bridging coil H^2 relative to the remote end of the main line section are in series with each other.

I may use any possible number of bridging coils on the tracks in order that I may deal successfully with complicated junctions and the like, no alteration in the method of controlling signals being contemplated.

If the lamps used in my invention are of low resistance the change in the resistance of the circuit due to the incandescence of the filaments will not affect the working of my invention if the strength of the current 110 in the white circuit be adjusted to the resistance of the black circuit while the red or green lamps are glowing. The variation in resistance of the timing lamp need not be taken into account. I add the following observations on the working of my invention:—If the cut-out fails to respond to the increased current the signal will fly back to danger when the train enters the section. If the failure occurs when the train leaves 115 the section the green lamp will not glow after the passage of the train and the signal lever cannot be pulled to safety. If the battery current fails the signal lever will fly back to danger and no light will glow 120 (the indication of "train in section"). If the white circuit be disconnected while the signal is at danger the lever might be pulled to safety with an effort if the control be direct while a train is in the section but the 125 130

failure of the glow lamp 9 inserted in the white circuit would give a sufficient warning. If the white circuit be disconnected while the signal is at safety the red lamp

5 will continue to glow after the passage of the train over the insulated rail length R^1 . If the black circuit be disconnected the green lamp cannot glow.

Ordinary mechanical or electrical interlocking completes the chain of safety. It is evident that with so much resistance in circuit a battery of fairly high voltage must be used.

In calculating the resistance of the bridging coils it is necessary to aim at as great an increase as possible upon the normal current passing through the black circuit, such increase being consequent upon the cutting out of one of the high resistances. It is the 15 difference between the normal and the strengthened current in such circuit which governs the strength of the current in the white circuit the function of the latter current as aforesaid, being to hold the signal 20 lever, semaphore, or controlling device. The magneto-motive force of the electro-magnets and the amount of current required for the lamps must also be considered. I may 25 relay separate currents for the lamps but 30 this is obviously undesirable. The armature of the cut-out device is preferably gravity controlled. I may use indicators other than lamps or may dispense with indicators 35 altogether.

35 Where freight wagons having metal wheels are included in a passenger train such vehicles should be placed immediately behind the tender unless the wheels of all vehicles are rendered conductive. If only 40 the wheels of freight trains are conductive it will be observed that my invention will serve to distinguish between freight and passenger trains.

What I claim as my invention and desire 45 to secure by Letters Patent is:—

1. In a railway signal control system the combination of a length of railway track having an insulated portion at each end thereof, a resistance connecting each insulated length of rail with the opposite rail each of such resistances being contained in a circuit of variable resistance, a plurality of locking electro-magnets each having opposing windings a winding of each of said 55 electro-magnets being contained in the said circuit of variable resistance; such combination being so characterized that a train passing over either of said insulated portions short-circuits the resistance between said 60 rails and causes an increase in the current strength in the said circuit of variable resistance and a diminution in the strength of the magnetism in said electro-magnets.

2. In a railway signal control system the 65 combination of a length of railway track

having an insulated portion at each end thereof, a resistance connecting each insulated length of rail with the opposite rail each of such resistances being contained in a circuit of variable resistance, a plurality 70 of locking electro-magnets each having opposing windings a winding of each of said electro-magnets being contained in the said circuit of variable resistance, a cut-out relay in said circuit; such combination being 75 so characterized that a train passing over said insulated portions of track short-circuits resistance in the said circuit of variable resistance and strengthens the current therein, thereby actuating said relay and 80 causing an additional resistance to be eliminated from said circuit.

3. In a railway signal control system the combination of a length of railway track having an insulated portion at each end 85 thereof, a resistance connecting each insulated length of rail with the opposite rail each of such resistances being contained in a circuit of variable resistance, a plurality 90 of locking electro-magnets each having opposing windings a winding of each of said electro-magnets being contained in the said circuit of variable resistance, a cut-out relay in said circuit controlling a resistance therein; such combination being so characterized 95 that, said cut-out relay having been actuated by the short-circuiting through a train's wheels and axles of resistance between the rails, said locking electro-magnets are no longer able to retain an armature when said 100 resistance between the rails is no longer short-circuited.

4. In a railway signal control system the combination of a length of railway track having an insulated portion at each end 105 thereof, a resistance connecting each insulated length of rail with the opposite rail each of such resistances being contained in a circuit of variable resistance, a plurality of locking electro-magnets each having opposing windings a winding of each of said 110 electro-magnets being contained in the said circuit of variable resistance, a cut-out relay in said circuit controlling a resistance therein, a plurality of indicators in the said circuit of variable resistance; such combination being so characterized that said cut-out relay being actuated by the passage of a 115 train over an insulated portion of track said indicators are operated by the consequent 120 increase in the current in the said circuit of variable resistance.

5. In a railway signal control system the combination of a plurality of railway tracks, a plurality of insulated lengths of track, a 125 resistance coil connecting each insulated length of rail with the opposite rail each of such rails being contained in a circuit of variable resistance, a plurality of locking electro-magnets each having two opposing wind- 130

ings one of each of such windings being contained in the said circuit of variable resistance and the other of such windings in a circuit of invariable resistance, a cut-out relay in the said circuit of variable resistance and controlling a resistance therein; such combination being so characterized that a train short-circuiting one of said resistances between the rails increases the strength of a current in the said circuit of variable resistance, actuates said relay, and varies the strength of the magnetism in said locking electro-magnets.

6. In a railway signal control system the combination of a length of railway track having an insulated portion at each end thereof; a circuit of variable resistance containing a resistance coil bridging each insu-

lated length of rail with the opposite rail and also containing the magnetizing coils of a 20 cut-out relay acting on resistance in said circuit and also containing coils appertaining to two locking electro-magnets; a circuit of invariable resistance containing a regulating resistance, and coils appertaining to said locking electro-magnets; such combination being so characterized that the currents in the two said circuits induce opposing magnetisms in each of said locking electro-magnets.

In testimony whereof I have hereunto set my hand in the presence of two witnesses.
